RADIO DIRECTION FINDER

Maurice A. Warren, Los Angeles, Calif., assignor to
Vec/Trak Research & Development Corporation,
Elmsford, N.Y.

Filed Mar. 8, 1973, Ser. No. 339,410

Term of patent 14 years

Int. Cl. D14—03

U.S. Cl. D26—14 K

FIG. 1 is a side elevational view of a radio direction finder showing my new design, with the tuning module not included;

FIG. 2 is a top plan view thereof;

FIG. 3 is a bottom plan view;

FIG. 4 is a view similar to FIG. 1, showing the opposite side;

FIG. 5 is a front elevational view with the tuning module not included;

FIG. 6 is a rear elevational view;

FIG. 7 is a fragmentary view similar to FIG. 1 with the tuning module included; and

FIG. 8 is a view similar to FIG. 5 with the tuning module included.

I claim:

The ornamental design for a radio direction finder, substantially as shown and described.
